G. G. STAINES.
ADJUSTABLE HORSE,
APPLICATION FILED OCT. 20, 1917.

1,271,095.

Patented July 2, 1918.

UNITED STATES PATENT OFFICE.

GUY GARFIELD STAINES, OF ALBION, NEW YORK, ASSIGNOR TO MYRTLE O. STAINES,
OF TORONTO, CANADA.

ADJUSTABLE HORSE.

1,271,095.

Specification of Letters Patent.

Patented July 2, 1918.

Application filed October 20, 1917. Serial No. 197,550.

To all whom it may concern:

Be it known that I, GUY G. STAINES, a citizen of the United States, and a resident of Albion, in the county of Orleans and 5 State of New York, have invented a new and useful Adjustable Horse, of which the following is a specification.

My invention relates to adjustable trestles or horses designed to be used by masons, 10 carpenters, paperhangers, painters, plasterers and such like artisans to support a temporary staging or floor upon which to stand and work, or for like supporting purposes; and particularly to that class of adjustable trestles in which the supporting 15 legs thereof are independently adjustable, so that the trestle may be adjusted into a level position notwithstanding that the surface upon which it stands may be irregular 20 in contour.

The objects of my invention are to provide an improved adjustable trestle or horse which may be easily and cheaply manufactured, which may be readily adjusted to various heights, and one in which the legs whereby the adjustment is provided for may be removed from the remaining portion of the device to thereby provide a compact and easily transportable structure. 25 A further object of my invention is to provide an adjustable trestle in which a single head portion may be used with legs of different lengths, to thereby extend the range of usefulness of the device; and to provide an adjustable trestle which will be 30 strong and rigid when in use and one in which the clamping devices for securing the adjustable legs and head portion together are of such form and construction that the 35 parts will be the more firmly clamped together the greater the load borne by the 40 trestle.

With the above and other objects of invention in view, my invention consists in 45 the improved adjustable trestle illustrated in the accompanying drawings, described in the following specification, and particularly claimed, and in such variations and modifications thereof as will be obvious to 50 those skilled in the art to which my invention relates.

The drawing accompanying and forming a part of this specification illustrates the preferred embodiment of my invention; although 55 it will be appreciated that the same

may be embodied in other forms, so long as it is within the scope of the concluding claims. In the said drawing wherein the same reference numerals are employed to designate like parts in several views, 60

Figure 1 is a view illustrating my improved adjustable trestle in perspective, and as set up for use; and,

Fig. 2 is a view upon a larger scale showing the clamping mechanism whereby the 65 adjustable legs are secured in place relative to the head.

Referring to the drawing, the reference numeral 4 designates a top bar or cross piece which serves as a support for the platform or table or whatever may be supported by the trestle. Permanently secured to the ends of this top bar and depending therefrom are short legs 5 which diverge in the manner illustrated, in order that the adjustable legs coöperating therewith may engage the surface upon which the trestle rests at points spaced apart from one another and that the device may be firmly supported. The lower ends of the fixed legs 70 5 are connected with one another by cross pieces 6; and suitable braces 7 extending between said cross pieces and the top bar 4 are ordinarily provided in order to provide a rigid and well braced structure. The 75 top bar 4, cross pieces 6, and braces 7 are permanently connected with one another, thus forming a single unitary structure which I refer to as the head portion of my adjustable horse or trestle. 80

The reference numeral 8 designates the adjustable legs of my improved trestle, the upper ends of which legs are in contact with and extend along the fixed legs 5, as shown, and are adjustable relative thereto, the 85 said legs being firmly clamped in place relative to the legs 5 when the device is set up for use by means of the clamping mechanism to be next described; although it will be appreciated that the adjustable legs are 90 are in no way permanently secured to the fixed legs and may be easily removed from the trestle.

The clamping means for securing the adjustable legs 8 and the fixed or built in legs 105 5 together when the trestle is in use is best shown in Fig. 2 of the drawing. Such clamping means comprises two spaced swinging clamping members 9 for each of the adjustable legs 8; said clamping members be- 110

ing of U-shape form, and the inner ends thereof being pivotally connected with the head portion by means of bolts 10, whereby the clamping members may swing upon said bolts as points of support. These clamping members are of such length that they normally occupy inclined positions, as shown, when the adjustable legs are clamped in position against the fixed or built in legs 5; 10 and the two clamping members which co-operate with each of the adjustable legs 8 are connected with one another through connecting bars 11, so that both the clamping members associated with each adjustable leg 15 may be swung about their pivotal connections 10 by moving said connecting bars longitudinally of the legs. To this end the lower ends of the connecting bars are preferably extended, and provided with hooks 20 12, with which hooks flexible members 13 are connected. The bars may be pulled downward to release the adjustable legs either by taking hold of the free ends of the bars or by pulling upon the flexible members 13 if 25 the head portion of the trestle is adjusted to such a height that the lower ends of the bars cannot be readily reached.

The connecting bars 11 are shown as pivotally connected with the swinging clamping members 9 through pivots 14, from which it follows that the outer or free ends 15 of the clamping members may be simultaneously swung away from the outer edges of the adjustable legs 8 to thereby release the said legs; and a sliding or loose connection is 35 preferably provided between the upper ends of the bars and the pivots through which said upper ends are connected with the upper swinging clamping members, as by providing slots 16 in said upper ends through 40 which the pivot or fastening members 14 which connect the upper ends of the bars with the upper clamping members extend and within which slots said pivots may have a limited movement.

The reference numerals 17 designate springs (one associated with each of the clamping mechanisms above described), one end of each of which is connected with the 50 bar 11 of the clamping mechanism with which it is associated and the other end of which is connected with a fixed projection, preferably with the pivot whereby the upper clamping member 9 is connected with the leg 5. The purpose of these springs is to draw the connecting bars 11 upwardly, and thus move and hold the outer ends 15 of the clamping members in engagement with the outer face of the adjustable legs 8; and the 55 purpose of the loose connections provided by the slots 16 is to permit the two clamping members for each adjustable leg to adjust themselves to slight variations in width of the legs (measured outward from the fixed 60 legs 5 upon which they rest) at the points 65

where the outer ends of the clamps engage the said legs, so that there may be a slight relative movement between each two connected clamping members independent of the connecting bar extending between and operatively connected with them, and so that both the clamping members associated with each adjustable leg will grip the same with substantially equal force and have the same or substantially the same holding action in clamping the adjustable and the fixed legs together when the trestle is in use.

The upper ones of the swinging clamping members 9 are made somewhat wider than the adjustable legs which extends through them in order to permit the upper ends of oppositely located adjustable legs to be moved sidewise relative to one another so that said upper ends may be made to pass by one another and extend above the top bar 4, as illustrated; thus permitting a trestle equipped with a given set of adjustable legs to be adjusted between a lower position in which the fixed legs 5 rest upon the ground or other surface and an upper position in which the upper clamping members engage the extreme upper ends of the adjustable legs.

In view of the premises it will be appreciated that each adjustable leg may be independently adjusted relative to the fixed leg with which it is associated, to thereby permit the top bar 4 to be leveled even though the surface upon which the trestle rests may be irregular in contour; and that sets of adjustable legs of different lengths may be used with a given head portion in order to increase the range of adjustability of the trestle as a whole. Finally, when the trestle is loaded the outer ends 15 of the inclined clamping members 9 will be drawn into firm engagement with the outer or free edges of the adjustable legs (due to the tendency of the load to move the head portion downward), from which it follows that the holding action of the clamps will be the greater the greater the load borne by the trestle. It will also be appreciated that the adjustable legs may be readily removed from the head portion of the trestle and the trestle as a whole thus rendered compact and easily transportable, and that the head portion alone may be used as a trestle or horse of lesser height than the trestle considered as a whole, and considered as equipped with the adjustable legs.

Having thus described and explained my invention, I claim and desire to secure by Letters Patent—

1. An adjustable trestle or horse comprising a top bar; a plurality of fixed legs carried by and rigidly connected with said top bar; a plurality of adjustable legs in contact with and extending one along each of said fixed legs; and a plurality of clamping

mechanisms for securing said adjustable legs one to each of said fixed legs—each of said clamping mechanisms comprising two spaced pivotally supported clamping members the free ends of which are adapted to engage the outer or free edge of the adjustable leg with which they are associated; and a connecting bar operatively connected with each of said clamping members and 10 whereby said members may be operated to release said adjustable leg.

2. An adjustable trestle or horse comprising a top bar; a plurality of fixed legs carried by and rigidly connected with said top bar; a plurality of adjustable legs in contact with and extending one along each of said fixed legs; and a plurality of clamping mechanisms for securing said adjustable legs one to each of said fixed legs—each of said 15 clamping mechanisms comprising two spaced pivotally supported U-shaped clamping members extending about an adjustable leg and the free ends of which are adapted to engage the outer or free edge thereof; a connecting bar pivotally connected with each of said clamping members; and a spring operatively connected with said bar and adapted to force the free outer ends of said clamping members into engagement with the free 20 outer edge of said adjustable leg.

3. An adjustable trestle or horse comprising a top bar; a plurality of fixed legs carried by and rigidly connected with said top bar; a plurality of adjustable legs in contact with and extending one along each of said fixed legs; and a plurality of clamping mechanisms for securing said adjustable legs one to each of said fixed legs—each of said 25 clamping mechanisms comprising two spaced pivotally supported clamping members the free ends of which are adapted to engage the outer or free edge of the adjustable leg with which they are associated; and a connecting bar operatively connected with each of said clamping members and 30 whereby said members may be operated to release said adjustable leg; the connection between said connecting bar and one of said clamping members being loose so that the two clamping members in question may have a limited movement independent of one another.

4. An adjustable trestle or horse comprising a top bar; a plurality of fixed legs carried by and rigidly connected with said top bar; a plurality of adjustable legs in contact with and extending one along each of said fixed legs; and a plurality of clamping mechanisms for securing said adjustable legs one to each of said fixed legs—each of said 35 clamping mechanisms comprising two spaced pivotally supported U-shaped clamping members extending about an adjustable leg and the free ends of which are adapted to engage the outer or free edge thereof; a connecting bar pivotally connected with each of said clamping members; and a spring operatively connected with said bar and adapted to force the free outer ends of said clamping members into engagement with the free outer edge of said adjustable leg; the connection between said connecting bar and the upper one of said clamping members including a slot in which the pivot through which said elements are connected 40 with one another may have a limited amount of movement.

5. An adjustable trestle or horse comprising a top bar; a plurality of diverging fixed legs carried by and rigidly connected with said top bar; a plurality of adjustable legs in contact with and extending one along each of said fixed legs; and a plurality of clamping mechanisms for securing said adjustable legs one to each of said fixed legs—each of said 45 clamping mechanisms comprising two spaced pivotally supported U-shaped clamping members extending about an adjustable leg and the free ends of which are adapted to engage the outer or free edge thereof; a connecting bar pivotally connected with each of said clamping members; and a spring operatively connected with said bar and adapted to force the free outer ends of said clamping members into engagement with the free outer edge of said adjustable leg; the upper one of said clamping members being wider than the adjustable leg with which it coöperates, so that the upper 50 end of said leg may be moved sidewise and permitted to pass by the upper end of another adjustable leg.

GUY GARFIELD STAINES.
